UNITED STATES PATENT OFFICE.

ADELMER M. BATES, OF CHICAGO, ILLINOIS, ASSIGNOR TO BATES VALVE BAG COMPANY, OF CHICAGO, ILLINOIS, A CORPORATION OF WEST VIRGINIA.

STENCIL PRINTING PROCESS.

Application filed April 7, 1922. Serial No. 550,498.

My invention relates to a printing process wherein the ink is transferred from an inked surface through a stencil plate onto the material to be printed. The object of 5 my invention is to provide a process of the character described which will give exceptionally clear cut results with absence of smearing or spreading of the characters. My more specific objects will appear as the 10 description proceeds.

I illustrate my invention more or less diagrammatically in the accompanying drawings, wherein—

Figure 1 is a diagrammatic view of a 15 stencil-producing apparatus;

Figure 2 is an example of a stencil plate;

Figure 3 illustrates the mounting of the 20 stencil plate, and

Figure 4 is a diagrammatic view of one 25 type of printing press with the stencil plate in position thereon.

Like parts are indicated by like characters throughout the drawings.

A is any suitable stencil machine, the 30 details of which do not concern the present application, and B illustrates a stencil card or plate of metal, fibre or any suitable material in the course of preparation in the stencil machine. C is a finished stencil plate 35 provided with the lettering C¹ and perforated at its corners, as at C².

In Fig. 3 the plate is shown as suspended 40 in front of any suitable platen D, which is provided with knobs, posts or projections D¹ at the side of the working surface, mounted, for example, on the arms D² projecting therefrom. D³ are any suitable 45 springs or yielding means secured at one end to the posts and at the other to the perforated corners of the stencil.

E is any suitable printing press having 50 the platen D mounted thereupon, with the posts and springs as above described. The platen is provided with a yielding or 55 resilient surface E¹, which may comprise a thin sheet of rubber or other suitable material. Upon this surface is supported the material to be printed, which is shown in Fig. 4 as an intermittently moving strip F 60 drawn from a roll F¹, through the guiding element F², across the aligning guides or rollers F³, which serve to align it across the platen. F⁴ is a reciprocating material-gripping element, the details of which do not 65 concern the present application, which

serves to draw the strip F intermittently across the face of the platen and beneath the stencil. F⁵ is a roll of printed material, although it will be understood that the material thus printed need not be returned to 70 a roll but may, if desired, be severed. The stencil plate C is supported above the strip F by the posts and yielding means alluded to.

G is any suitable printing head pivoted 75 to the press as at G⁴, and adapted to be rotated back and forth into and out of contact with the platen. G¹ is the ink-bearing surface, which consists preferably of a block of rubber, although other materials, such as plain metal or flat fibre board, 80 might be satisfactory. G² is any suitable inking element and G³ is the usual inking table.

Since it is obvious that my process may 85 be carried on with numerous other mechanical means and is not by any means limited to the means herein disclosed, it will be sufficient to say that the printing head is rotated into contact with the stencil and strip, which it clamps against the platen, the rubber surface being automatically inked at each reciprocation of the printing head. As the printing head returns to withdrawn 90 position, the reciprocating element F⁴ feeds the material forward for the next impression.

It will be obvious that while I have shown 95 the process as applied to a press for printing from a continuous roll, it might be applied to any other suitable type of press, for example a press adapted to operate on single sheets or cards.

My process will be apparent from the foregoing description, but especial attention 100 should be given certain features.

The inked surface, which we may call 105 a die block, carrying its ink, presses against and picks up the yieldingly mounted stencil plate on its forward stroke, forcing it down upon the work to be printed, and depositing its ink through the characters or apertures in the stencil plate. The action of the soft pad or backing underneath the stencil plate embosses the work, forcing the cloth or paper up through the openings in the stencil plate to meet the down-pressed rubber, ink-covered, die block, which, being resilient, also penetrates the apertures of the stencil. The result is a beautifully clear 110 cut line of letters, since the squeeze of the

resilient pad or block fills out the entire cut-out area of the stencil letters and produces a letter of extremely sharp outline.

As the press opens, the inking die block 5 is withdrawn and the yieldingly mounted stencil plate withdraws with it, rising out of contact with the work. This removes the stencil plate by a substantially right line motion, which avoids any tendency there 10 might be, if one edge of the stencil were lifted first, for the ink to follow along the line of parting between the stencil and the printed material. It will be noted, also, that the stencil is lifted from the printed 15 surface while still held against the inked surface, which aids in parting the ink cleanly at the edges of the stencil perforations. Further, the stencil is made of or entirely surfaced with a material to which ink will 20 not markedly adhere, and this vastly reduces the probability of any smearing or spreading of the characters.

The resilient pressure applied over the 25 entire surface of the material opposite the stencil draws the material being printed very snugly across the edges of the perforations in the stencil plate, resulting in sharper outlines of the printed characters, and also allows the use of a thicker and 30 consequently more durable stencil plate than would be practicable if the material being printed were not thus pressed into the stencil perforations.

While my process is suitable for use in 35 printing on many different materials, it is especially adapted to printing on cloth, crepe paper, and similar material that may be readily pressed into the stencil openings to an appreciable extent.

40 By my process, the ink-carrying surface leaves each character covered with a film of liquid ink. This film forms characters having a very desirable appearance, and the tendency, which this liquid ink would 45 otherwise have to run at the edges of the characters and produce a smeared effect is overcome by the special features of my process.

I claim:

50 1. The process of printing upon flexible material, which consists in positioning said material and a non-absorbent inked surface on opposite sides of a stencil, and pressing said material against the stencil by means 55 of a uniform resilient pressure which causes the material to enter the perforations in the stencil.

55 2. The process of printing upon flexible material, which consists in positioning said material and a non-absorbent inked surface on opposite sides of a stencil and pressing said material and inked surface into perforations in the stencil by means of uniform 60 resilient pressure back of each.

65 3. The process of printing upon flexible

material, which consists in positioning a stencil between a non-absorbent ink-carrying surface and successive portions of said material, making successive impressions upon said successive portions by pressing said portions against the stencil by uniform resilient pressure, and inking said surface between each successive impression. 70

4. The process of printing upon flexible material, which consists in positioning a 75 stencil between a non-absorbent ink-carrying surface and successive portions of said material, making successive impressions upon said successive portions by pressing said surface and said portions against the stencil 80 by uniform resilient pressure back of each, and inking said surface between each successive impression.

5. The process of printing, which consists in positioning material to be printed 85 and a non-absorbent inked surface upon opposite sides of a stencil, pressing said material and surface against the stencil and thereby transferring ink through the 90 stencil onto said material, and removing the inked surface from the material while still pressing the stencil against said surface so that the stencil will part from said material before it does from said surface. 95

6. The process of printing upon flexible 100 material, which consists in positioning said material and an inked surface upon opposite sides of a stencil, pressing said material and inked surface against the 105 stencil by uniform resilient pressure back of each, and separating the stencil from the material while continuing to hold the stencil in contact with the inked surface.

7. The process of printing upon flexible 110 material, which consists in pressing a stencil and said material together by means of uniform resilient pressure back of said material, passing liquid ink through the 115 perforations of the stencil onto the material, and then removing the stencil from the material by a substantially right line movement.

8. The process of printing, which consists in positioning between an ink-carrying surface and successive portions of said material a stencil having a surface not adherent to ink next to the ink-carrying surface, successively pressing the ink-carrying surface by uniform resilient pressure against said surface and said successive portions and thereby transferring ink through perforations in the stencil onto said portions, and after each impression parting the stencil and material while maintaining contact between the stencil and ink-carrying surface, then parting the stencil and ink-carrying surface, and then re-inking said surface. 120

9. The process of printing upon flexible material, which consists in positioning said material and an inked surface upon opposite 125

sides of a stencil having an entire surface non-adherent to ink, pressing said material and inked surface into perforations in the stencil by means of uniform resilient pres-

sure back of each, and parting the stencil and material while maintaining contact between the stencil and inked surface.

10. The process of printing upon flexible material, which consists in positioning, between an ink-carrying surface and successive portions of said material, a stencil having its entire surface non-adherent to ink, pressing said ink-carrying surface and each successive portion of said material 15 into perforations in the stencil by means of uniform resilient pressure, after each impression parting the stencil and material

while maintaining contact between the stencil and ink-carrying surface, then parting the stencil and ink-carrying surface, 20 and then re-inking said surface.

11. The process of printing upon a web of flexible material, which consists in drawing the web intermittently past a stencil and while the web is at rest pressing a non-absorbent ink-carrying surface and the web against opposite sides of the stencil by 25 resilient pressure back of each so that ink is transferred from said ink-carrying surface through the stencil onto the web. 30

Signed at Chicago, county of Cook and State of Illinois, this 5th day of April, 1922.

ADELMER M. BATES.
